UNITED STATES PATENT OFFICE.

ROSA CAMPS VIUDA DE QUIRICO CASANOVAS, FEDERICO SCHWARTZ, AND ENRIQUE GIL-CAMPORRO, OF BARCELONA, SPAIN.

METHOD OF MANUFACTURING AN AGGLOMERATED OR COMPOSITE PRODUCT.

No Drawing. Application filed November 28, 1925, Serial No. 72,028, and in Spain January 16, 1925.

This invention relates to the production of synthetic wood and has for its object to provide a method by the practice of which a new product is obtained which is capable of replacing other natural and artificial products with advantage. In the manufacture of this agglomerated or composite product paper of any kind or origin is used as the raw material and the necessary number 10 of sheets thereof are placed together, the one above the other, and attached to each other by means of a varnish which is transformed into an agglutinant in the course of the manufacture of the product.

15 The varnish which acts as the agglutinant in the present application, forms the subject matter of the pending application for Patent Ser. No. 16,817, which has matured into Patent No. 1,621,438, of March 15, 1927, and 20 consists of an ammoniacal soap comprising gums, resins and fatty acids of certain oils, with or without the addition of albumen, casein or other similar substances, and is obtained by saponifying the gums and resins 25 with ammonia or other volatile alkaline radicals in the presence of ricinate of ammonia.

According to the present invention the method of producing the agglomerated product consists essentially in taking sheets 30 of paper of the quality, dimensions, colour, and the like adjudged to be suitable for the conditions to be fulfilled by the final agglomerated or composite product, and applying to these sheets a watery solution of the 35 above mentioned soap to which may be added any desired colouring materials or the like. The paper after the application of the soapy solution is dried for the purpose of removing the water and the ammonia of the agglutinating varnish and the sheets are then assembled in superposed relation according to the thickness desired in the product and are compressed hot whereby the soap or varnish previously applied softens and acquiring 45 properties of an agglutinant fastens the sheets together so as to form a compact body.

In carrying out the invention the varnish or soap may be applied to the paper by means of a machine such as is used for staining or varnishing paper, which applies a 50 uniform layer of the varnish or soap on one or both sides thereof. This operation may also be effected simply by immersion by causing the paper to pass continuously

through a receptacle containing the solution of soap or varnish.

When the paper has been varnished it is conveyed to a dryer or stove in which it is allowed to dry in order to effect evaporation of the water contained in the varnish 60 and also of the ammonia whereby the varnish is converted into a fatty and resinous substance suitable for use as an agglutinant.

After the paper has been dried it is preferable before assembling the sheets together 65 for the purpose of agglomerating them, to pass it through a calender so that it acquires a smooth and level surface so that on the subsequent assembly of the sheets they have a better contact with each other and the operation of securing them together is facilitated.

To effect the agglomerating operation a suitably heated press or mould is utilized so that, by the combined action of pressure and temperature the varnish may be softened 75 and may act as an agglutinant to unite the sheets of paper perfectly with each other. The pressure and the temperature used in the agglutinating operation are a complex function of the gums and resins used in the 80 manufacture of the aforesaid soapy varnish, and also of the structure and constitution of the paper used as the raw material and the qualities of hardness and resistance desired in the final product. In any case the temperature must be below 200° C. and in practice any temperature below this point may be adopted as will give the best softening of the agglutinating varnish and afford the 85 most intimate adhesion or union between the 90 sheets of paper.

The product obtained by the practice of the present invention is in its composition and structure very similar to wood and excels in its qualities the best timber. It is 95 also capable of being machined like natural wood with the saw, lathe, or the like and its resemblance to these woods as regards appearance is so complete that on being machined it displays grain, veinings and rings 100 similar to those of natural woods. It is also capable of taking a polish at least equal to that of the best hard woods.

The new product is also characterized by a high degree of impermeability and heat 105 and electric insulating properties as compared with natural woods and other similar products.

It also possesses the following material advantages, among others over natural woods, viz:—

(1) Greater homogeneity without the defects, knots and cracks which characterize natural woods.

(2) Much greater duration inasmuch as it is free from the putrefactive materials which in general give rise to decay and dis-eases of natural woods.

(3) Greater qualities of strength which are constant in all ways and directions. This property is much in contrast to natural woods which only present a relative constancy of the value of their strength along a given direction of the grain.

(4) The very valuable property that it can be manufactured into blocks, boards and sheets of such measurements and dimensions as required.

(5) The interesting possibility of being able to provide the product with cores of very strong substances, thus securing features of strength unattainable by natural woods.

(6) And in addition to all the possibilities of an artistic character, the possibility of being able to make translucent products.

We claim:

1. The method of manufacturing synthetic wood which comprises applying to sheets of vegetable fibre a coat of a watery solution of a complex soap of resins and fatty acids of certain oils saponified with ammonia,

leaving these sheets of vegetable fibre to dry ³⁵ in order to eliminate the water and ammonia, and then in assembling said coated sheets in superposed relation and subjecting them to the action of pressure and heat.

2. The method of manufacturing synthetic ⁴⁰ wood, which comprises applying to any suitable kind of sheets of vegetable fiber a coat of a watery solution of a complex soap of resins and fatty acids of certain oils saponified with ammonia, leaving the sheets ⁴⁵ to dry in order to eliminate the water and the ammonia, calendering the sheets to leave them with a smoother and more even or uniform surface and finally superposing said sheets and uniting them together into a ⁵⁰ homogeneous body by the action of pressure and heat.

3. The method of manufacturing synthetic wood which consists in applying to sheets of vegetable fiber a coat of a watery ⁵⁵ solution of a complex soap of resins and fatty acids of certain oils, with the addition of a solution of albumen and colouring matter, allowing said sheets to dry, calendering them when dry and lastly superposing them ⁶⁰ and uniting them into a homogeneous body by the action of heat and pressure.

In testimony whereof we have signed our names to this specification.
